UNITED STATES PATENT OFFICE.

CHARLES D. ANDERSON, OF CHICAGO, ILLINOIS.

SPARK-INTENSIFIER TERMINAL.

Application filed March 5, 1921. Serial No. 449,973.

My invention belongs to that general class of devices known as spark intensifiers, and relates particularly to an intensifier that may be used as an auxiliary terminal device in connection with sparking devices such as spark plugs or the like. The invention has among its objects the production of a construction of the kind described that is simple, durable, dependable, convenient, inexpensive, compact, efficient, pleasing and attractive in appearance and satisfactory for use wherever found applicable. The invention has among its further objects the production of a device which may be rigidly assembled wherein there will be no shifting or variation in the relationship of the parts, and which will be gas tight and free from any short-circuiting. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a vertical section taken substantially on line 1—1 of Fig. 2, showing my device as applied to a spark plug;

Fig. 2 is a sectional view taken substantially on line 2—2 of Fig. 1;

Figs. 3, 4 and 5 are sectional views similar to Fig. 1, showing modifications of my invention;

Fig. 6 is an elevation of another embodiment of my invention; and

Fig. 7 is a section taken substantially on line 7—7 of Fig. 6.

In the preferred embodiment of my invention, the device consists substantially of what may be termed a "base element", a "dielectric element", a "top element" and a "retaining element". Referring to the drawings, 1 and 2 represent the top and base elements or electrodes which are arranged in alignment with an air gap between the same. In the air gap is arranged the dielectric element or spacer member 3, preferably of mica, bakelite, glass, porcelain or the like and of the desired size, which said member in the preferred construction is provided with one or more apertures or passages therethrough, and also with a central aperture or passage 5. The opposed end faces

of the top and base terminals are adapted and formed to abut the opposed faces of the member 3, which spaces and prevents movement of the parts 1 and 2 toward each other. Ordinarily I prefer to make the member 3 approximately .015 to .090 inch thick, depending upon the use intended, and I have found that the apertures may be omitted if desired in some instances, particularly when the member 3 is not too thick.

The base element 1, which is preferably made of brass or other suitable electrical current-conducting material, has an upper flange 6 which is preferably of non-circular shape, such as square, rectangular or the like, or said flange may be milled, knurled or punched, or have projections thereon to suitably roughen it. Adjacent the flange is an annular groove or channel 7, the flange 6 forming one side of the groove, the other side wall being formed by a flange 8. In order to decrease the amount of material and reduce the weight of the base terminal, I have grooved or cut away an annular channel 9 between the flange 8 and the bottom which constitutes a base flange 10. The said flange 10 is preferably polygonal in shape, so it may be turned with a wrench, pair of pliers or other suitable tool. If desired, a threaded hole may be provided partially or entirely through the base terminal and axially thereof, which said threaded hole is adapted to engage the cooperating threaded electrode of the electric device to which it is to be adapted, as for instance to the spark plug terminal shown in Fig. 1.

The upper or top electrode 2, also preferably made of brass or other good conducting material, has a lower flange 12 and an annular groove 13 and a retaining flange 14 similar in shape and size to the portions 6, 7 and 8 respectively of the base electrode, there being also a groove or recess 15 above the retaining flange for receiving and holding wire clip terminals as commonly used in ignition systems, and said upper terminal may also be provided with an axially threaded bore 16 adapted to receive a terminal screw 17 therein, so that a conductor 18 may be positioned or secured between the terminal screw 16 and the outer face of the top terminal. If the terminal wire 18 is connected to the top terminal and the base terminal to the spark plug, the spark will jump through the apertures 4 and 5 of the intermediate spacing member 3.

In order to hold the terminal and interme-

diate member in their predetermined relationship, as well as inclose the spark gap chamber so that there can be no possibility of foreign matter entering the chamber, I provide the 5 outer binder or retaining member which I have hereinbefore referred to as the retaining element, which is made of bakelite, glass, porcelain or other suitable insulating material. The retaining member or element may 10 be molded, shrunk, compressed or otherwise suitably secured about the three members so as to hold them rigidly together, whereby the parts constitute substantially a unitary structure. As shown, the member 19 has inturned 15 end flanges 20 closely fitting into the grooves 7 and 13 of the terminals. Inasmuch as the flanges 8 and 12 of the opposed terminal ends, are non-circular in shape, or otherwise constructed as described, there is no tendency of 20 the parts to turn or rotate in the retaining member. The device when it is thus assembled forms a complete self contained unit, which may be used as a terminal on a spark coil, magneto, lightning arrester, generator, 25 spark plug, or as a terminal on any other electrical device of a similar nature to which it is applicable.

In Fig. 3, I have illustrated a similar intensifier or terminal wherein the base member 30 has an externally formed threaded stem extending axially therefrom, the remainder of the construction being substantially similar to that previously described. In Fig. 4, I have illustrated a device provided with an 35 upper or top terminal having a stem extension 22, which may be threaded or not, as desired, and the upper terminal is also provided with a threaded bore 23 extending axially therethrough and in registry with the bore 40 11 of the base terminal. If so desired, the modification shown in Fig. 4 may be used as ordinary terminal instead of a spark intensifier. In that case the electrode terminal of the electrical device to which it is connected 45 would extend through and engage both the upper and lower terminals at their bores 11 and 23, and the terminal parts then being in direct electrical contact there will be no spark jump through the air gap spaces provided 50 in the spacing member.

Fig. 5 illustrates an embodiment similar to that shown in Fig. 4, except that the bore 23 has been omitted. The various types of connections are provided on or for different 55 forms of electrical devices. It will be obvious from the preceding that the various terminals may be assembled or interchanged to give different combination of devices.

With the construction herein described, one 60 or more of the terminal parts may be associated together in a common retaining element, the number so associated depending upon the number required for any certain device or ignition system. I have illustrated 65 in Figs. 6 and 7 how the several terminals

may be applied to a panel, plate, disk, cover, or any other regular or irregular body 26, preferably made of insulating material, which may be molded, punched, compressed or otherwise formed to suitably carry the terminal parts 27 and maintain them in their desired relationship with each other. I have illustrated both terminal parts entirely imbedded in the insulating material but it may be readily understood that the several parts 70 75 may project about the surface of the body part or retaining element, if so desired. Such application is particularly suitable for electrical devices such as magnetos, timers, distributors, induction coils, coil boxes, arresters and generators, and functions to the fullest extent of efficiency in fulfilling the entire duty and purpose for which the device is designed.

From the preceding it will be seen that I 80 have produced a spark intensifier terminal which is extremely rigid, durable, attractive in appearance, which occupies very little more space than the ordinary terminal and one in which the spark gap is maintained 85 constant and unshifting, so that there will be no leakage of power, the same as before stated, may be used as an ordinary terminal element, the spark jump being eliminated, if so desired. Obviously, where the retaining 90 element is made of substance which is transparent, as for example glass, bakelite, or the like, the spark may be observed, so that it may be seen whether or not the combustion engine is receiving the proper spark to ignite 95 the charge.

I have hereinbefore referred to the spacer or washer 3 as a separate element which may be inserted between the parts and which may or may not be provided with apertures. It 100 might be noted, however, that the device may be constructed by assembling the electrode elements and leaving a space between the same so that when the retaining member is formed, poured, molded or pressed around the upper and lower electrodes the material 105 so used will flow or be forced between the upper and lower parts in the space between them thereby forming a distance spacer which is integral with the outer casing or retainer. I 110 therefore wish to be understood in the claims, that the means in the space for spacing the terminals may or may not be integral with the retaining element, this depending upon 115 the preference of the manufacturer and also in some cases upon the materials which may enter into the construction of the device.

Having thus described my invention, it is obvious that various immaterial modifications may be made in the same without departing from the spirit of my invention; hence I do not wish to be understood as limiting myself to the exact form, arrangement, construction and combination of parts herein shown and described, or uses mentioned.

What I claim as new and desire to secure by Letters Patent is:

1. In a sparking device of the kind described, the combination of a pair of electrode terminals having an air gap therebetween, an apertured disc between said terminals for positively spacing them and preventing contact therebetween, and a single separately formed integral means, encompassing said parts and interengaging with them for fixedly securing them together in their assembled relation.

2. In a spark intensifier of the kind described, a pair of axially aligned terminals having peripheral grooves thereon, an apertured spacing disc between the opposed ends of said terminals, and an insulating retainer fitting about said terminals and extending into said grooves to bind said terminals against said spacer and form a rigid structure.

3. In a device of the kind described, a pair of axially aligned terminals having peripheral grooves thereon, an apertured insulating spacing disc therebetween, and an insulating retainer formed about said terminals and extending into said peripheral grooves to clamp the opposed end faces of said terminals against said spacer and form an assembled structure.

4. In a device of the kind described and in combination, a pair of opposed terminals having an air gap therebetween, and a retaining member for locking said parts in their assembled relation, said terminals being apertured and having a registering aperture therebetween wherein the projecting electrode of a cooperating electrical device may be inserted an adjustable distance through said registering apertures.

5. In a device of the kind described and in combination, a pair of opposed terminals having an air gap therebetween, an apertured insulating member between said terminals and contacting with the opposed end faces thereof, and a retaining member for holding said parts in their assembled relation, said terminals having a registering aperture therebetween wherein an electrode member of a cooperating device may be inserted to connect said terminal parts together.

6. In a spark intensifier of the kind described, a pair of axially aligned terminals having peripheral grooves thereon, an apertured spacing member between the opposed ends of said terminals, and a transparent insulating retainer fitting about said terminals and extending into said grooves to bind said terminals against said spacer and form a rigid structure.

7. In a device of the kind described, a plurality of pairs of axially aligned terminals, each terminal having a groove thereon, an apertured spacing member between the opposed end of each pair of terminals, and an integral insulating plate having a continuous surface fitting about all of said terminals and projecting into said peripheral grooves to clamp and bind the terminals against said spacing member.

8. In a device of the kind described, the combination of a plurality of pairs of electrode terminals having air gaps therebetween, an apertured disc between the terminals of each pair thereof for accurately spacing them, and a single separately formed integral means encompassing said terminals and interengaging with them to hold them in assembled relation with each other and the apertured means.

9. In a device of the class described, a pair of axially aligned terminals having peripheral grooves thereon, an apertured insulating disc therebetween, and a single insulating retainer having a continuous surface formed about said terminals and extending into said peripheral grooves to clamp the opposed end faces of said terminals against said disc and to form an assembled structure.

10. In a device of the class described, a pair of axially aligned terminals having peripheral grooves thereon and an apertured spacing disc between the opposed ends of said terminals, and a transparent insulating retainer fitting about said terminals and extending into said grooves to bind said terminals against said disc and to form a rigid structure.

In testimony whereof, I have hereunto signed my name.

CHARLES D. ANDERSON.
